GARMENT TRIMMING MACHINE

Victor J. Sigoda, Great Neck, Jerry Sigoda, New York, and Joseph Cosentino, Richmond Hill, N. Y., assignors to Man-Sew Pinking Attachment Corp., New York, N. Y., a corporation of New York

Application November 25, 1941, Serial No. 420,350

25 Claims. (Cl. 164—71)

This invention relates to garment trimming machines, and more particularly to a dress or skirt trimming machine which is more particularly designed and intended for use by large scale production dressmaking establishments for accurately trimming or cutting dresses or other garments at high speed to the required predetermined length.

It is one of the objects of the present invention to provide a single-motor driven rotatable dress supporting form and cutting or trimming mechanism together with novel and effective means for smoothly and positively feeding the dress material to the rotating cutting member.

It is also another object of the invention to provide an improved mounting and arrangement of the operating motor with the cutting and feeding mechanism whereby they may be easily and quickly moved as a unit into and out of operative relation with the rotatable dress supporting form.

A further object of the invention is to provide an improved mounting of the feeding mechanism and means for operating the same from the motor driven cutter shaft.

An additional object of the invention is to provide an improved mounting of the rotatable dress supporting form and a drum connected therewith for unitary rotation and operative engagement by the feeding means, together with means for vertically adjusting said form relative to the axis of rotation.

It is a further general object of the invention to provide a garment trimming machine as above characterized which is comparatively simple in the construction and arrangement of its several parts, not liable to get out of order, and which may be operated at very high speeds with an appreciable increase in the quantity production of such trimmed garments over machines of this kind as heretofore used in the art.

With the above and other objects in view, the invention consists in the improved garment trimming machine and in the form, construction and relative arrangement of its several elements, as will hereinafter be more fully described, illustrated in the accompanying drawings and subsequently incorporated in the subjoined claims.

In the drawings wherein we have shown one simple and practical embodiment of the invention and in which similar reference characters designate corresponding parts throughout the several views:

Fig. 1 is a front side elevation, partly in sec-

tion, of one embodiment of our improved garment trimming machine.

Fig. 2 is a top plan view thereof, the garment supporting form being omitted.

Fig. 3 is a horizontal sectional view taken substantially on the line 3—3 of Fig. 1.

Fig. 4 is a vertical sectional view taken on the line 4—4 of Fig. 2, and

Fig. 5 is a rear side elevation of the machine.

In the illustrated embodiment of our invention, we have shown the movable parts of the mechanism mounted or supported upon a common base structure 5. Preferably, this base structure is in the form of a hollow elongated casting of light metal, such as aluminum alloy, and it is of the required form and dimensions to provide the requisite stability for the movable machine parts.

At one of its ends the base casting 5 is centrally formed on its top wall with an upstanding bored boss 6 to receive the lower end of a vertical shaft or spindle 7 which is supported at the upper and lower ends of said boss by the anti-friction bearings indicated at 8. A member 9 loosely surrounds the spindle 7 for vertical movement relative thereto and supports a bearing plate 10 having a sleeve 11 extending downwardly through an opening in the member 9 and receiving the nut 12 threaded on the lower end of said sleeve. A base member 13 is rotatably supported on the member 9 by the anti-friction bearing means 14 and is rigidly connected with respect to forces in a horizontal plane by means of a plurality of vertical rods 15 with the member 16 fixed to the bottom face of the dress supporting form 17.

The rods 15 are vertically movable through spaced openings formed in the hub portion 20 of the internal spider 19 of a metal drum 18, the said spider hub 20 being rigidly fixed in any suitable manner to the spindle 7. Preferably, the cylindrical wall of the drum 18 has an inwardly inclined upper end portion 18' for the purpose of directing the material of the garment supported on the form 17 to the feeding and cutting mechanism to be later described.

The member 16 has free sliding movement along the spindle 7 and the upper end portion of said spindle extends loosely into an axial bore 21 in the form 17.

At the opposite end of the base 5, a tubular column or standard 64 is suitably mounted at its lower end. Within this standard a threaded adjusting rod 65 is suitably mounted, and upon the same the traveling nut 66 has threaded engagement. One end of a horizontal rod 67 is

suitably fixed to this nut and extends outwardly therefrom through a vertical slot in the wall of standard 64, the other end of said rod being fixed to the member 9. Above the standard 64 a suitable hand wheel 68 is fixed to the rod 65, whereby said rod may be conveniently rotated. It will be understood from this description that by rotating the rod 65, the member 9 and the rods 15 may be vertically moved to adjust the form 17 relative to the spindle 1 and the drum 18 and thereby position said form in vertically spaced relation from the drum.

The trimming and feeding mechanism is mounted and arranged upon the base 5 with respect to the form 17 and drum 18 in the following manner. A vertical pin or rod 22 is rotatably supported at its lower end in a suitable bearing indicated at 23, on the top wall of the base structure 5. To this rotatably mounted pin, one part 24 of a double clamping member is securely fixed, the other part 25 thereof having clamping engagement with one end of the rod 26 disposed at right angles to the vertical pin or rod 22. The other end of this rod 26 is rigidly connected by means of the clamping device 27 with a tubular rod 28. To this rod at one of its ends a supporting bracket 29 for an electric motor 30 is rigidly connected as at 31. The other end of the rod 28 carries a supporting bracket 32 for the gear housing 33.

The vertically positioned drive shaft of the motor 30 has a belt wheel 34 fixed to its upper end and connected by drive belt 35 with a belt wheel 36 on the lower end of vertical shaft 37, which is suitably mounted in a depending bearing 33' on the gear housing 33 and above the elongated housing structure 38 enclosing said wheels and the driving belt. One side wall of this housing structure has a lateral projection 39 connected with rod 28. The upper end of shaft 37 is provided with a pinion 40 in constant mesh with the gear 41 mounted in housing 33 upon the vertically positioned shaft 42 in fixed driving relation therewith.

The housing 33 is formed with an upwardly and laterally extending arm 43 upon which there is rigidly fixed a horizontally disposed supporting member 44. On each end of this supporting member freely rotatable vertically spaced apart feed belt sheaves or wheels 45 and 46 respectively, are suitably mounted. The corresponding sheaves 45 and 46 are engaged by the endless vertically spaced apart feed belts 47.

To the vertical shaft 42 and immediately below the plane of the lower edge of the drum 18, a cutting or trimming wheel 48 is fixed. While various means might be provided for driving the feed belts 47 and rotating drum 18 and form 17 from the motor 30, we preferably transmit the driving power in the following manner.

Above the cutter 48 vertically spaced apart drum engaging members 49 are fixed to the shaft 42 and between these members a drive wheel 50 for the endless belt 51 is also fixed on said shaft. This drive belt is engaged with a similar driving wheel 52 arranged between and secured to the sheaves 46 engaged with the feed belts 47.

Upon the inner side of the gear housing 33, a horizontally disposed lever 53 is pivotally mounted intermediate of its ends, as at 54. One end of this lever carries a pressure roller 55 freely rotatable about a vertical axis and disposed in the plane of the cutting or trimming wheel 48. The other end of this lever 53 carries an adjustable screw 56 and between one end of this

screw and the bracket arm 57 on the gear housing 33, a suitable form of spring 58 is interposed. It will be evident from this construction that by adjusting the screw 56, the spring 58 may be properly tensioned to regulate the pressure engagement of roller 55 with the periphery of the cutter wheel 48.

While any preferred means may be employed for controlling the supply of operating current to the motor 30, we preferably provide the tubular rod 60 having a horizontal lower end portion 61 fixed in the arm 43. The current supply wires to the motor, indicated at 62, extend through the tubular rod 28 into the lower horizontal end 61 of the rod 60 and then upwardly through the vertical portion thereof to a suitable hand operated switch indicated at 63, mounted on the upper end of said rod. This rod provides a convenient means whereby the cutting and feeding mechanism with the drive means therefor may be bodily swung as a unit about the axis of pin or rod 22 into and out of operative relation with the drum 18. However, it will be understood that we may also use a pedal operated or other form of manual control switch for the operating motor if desired.

Having now described the several mechanical features of the apparatus, its operation will be understood as follows.

Before moving the cutting and feeding mechanism into operative relation with the drum 18, the skirt, dress or other garment is draped upon the form 17 with its lower end portion circumscribing the wall of the drum 18. In accordance with the desired predetermined length of the garment after trimming, the hand wheel 68 is then operated to vertically adjust the form 17 relative to the drum 18 and cutter 48, in the manner above described and properly position the lower edge of the garment with respect to said cutter. The operator now swings the trimming and feeding assembly into operative position as shown in the drawings, so that the members 49 will exert frictional pressure against the vertical drum wall, it being understood, of course, that such frictional pressures are applied through the interposed fabric material.

Current is now supplied to the motor 30, and rotation is transmitted through the drive belt 35 and gearing 40, 41 to the cutter wheel shaft 42. This shaft transmits rotation to the belt drive wheel 50, which in turn drives the vertically spaced feed belts 47. The members 49 also driven through the shaft 42 transmit rotation to the drum 18, and through the connecting rods 15 to the form 17. As the form is thus rotated with the drum, the folds of the garment material, in advance of the cutting member 48 are engaged by the feed belts 47 which press the same against the periphery of the drum wall and smoothly feed the dress or skirt material between the cutter wheel 48 and the disk 55. It will be understood that as the drum 18 and form 17 are rotatably supported on anti-friction bearings, said drum and form will be easily rotated by the members 49. It will further be appreciated that such a machine is capable of operation at very high speeds so that it is particularly desirable for large scale factory production of accurately trimmed garments.

In the drawings, we have illustrated a type of trimming cutter 48 which produces a serrated or pinked edge on the garment. However, it is apparent that if desired, various other types of cutters might be used.

Further, while we have herein disclosed a practical embodiment of our present invention, which in actual service has proved to be very satisfactory and highly efficient, it is, nevertheless, to be understood that in so far as the essential features thereof are concerned, they might also be exemplified in various other alternative structural forms. Accordingly, we reserve the privilege of resorting to all such legitimate changes in the construction and relative arrangement of 10 the various elements as may be fairly comprehended within the scope of the appended claims.

We claim:

1. In a garment trimming machine, a rotatably mounted garment support, a rotatable cutting member, and a common operating motor for 15 said garment support and cutting member.

2. In a garment trimming machine, a rotatably mounted garment support, a rotatable cutting member, means to engage the garment and 20 feed it to said cutting member, a single operating motor, means for transmitting rotation from the motor to the rotatable garment support and cutting member, and additional means operated by one of the motor driven parts for actuating 25 said feed means.

3. In a garment trimming machine, a rotatably mounted garment support, a rotatable cutting member, means for feeding the garment material to said cutting member including an endless flexible feed belt, and a single operating motor for 30 the garment support, the cutting member, and said feed belt.

4. In a garment trimming machine, a rotatably mounted garment support, a rotatable cutting member, means for feeding the garment material to said cutting member including a drum and means connecting the drum with the support for 35 unitary rotation, an endless feed belt cooperating with the drum to feed the garment material to the cutting member, and motor driven operating means for the cutting member, garment support and drum, and said feed belt.

5. In a garment trimming machine, a rotatably mounted garment support, a drum mounted below the support, a rotatable cutting member to which the lower edge portion of the garment is directed by said drum, and an endless flexible belt coacting with the drum to feed the garment material to 40 said cutting member in the rotation of the support.

6. In a garment trimming machine, a rotatably mounted garment support, a drum below said support and connected therewith for rotation about a common axis, a rotatable cutting member, an operating motor therefor, and means operatively driven by one of the motor driven parts and coacting with the wall of said drum to rotate 45 the drum and garment support.

7. In a garment trimming machine, a rotatably mounted garment support, a drum below said support and connected therewith for rotation about a common axis, a rotatable cutting member, an operating motor therefor, means operatively driven by one of the motor driven parts and coacting with the wall of said drum to rotate the drum and garment support, and additional means having driving connection with said last named means for feeding the garment material to the cutting member.

8. In a garment trimming machine, a rotatably mounted support, a rotatable cutting member, a drum for directing the lower edge portion of the garment to the cutting member, means connecting the drum to the support for rotation as a unit

therewith about a common axis, and means for vertically adjusting the support independently of the drum.

9. In a garment trimming machine, a rotatably mounted support, a rotatable cutting member, a drum for directing the lower edge portion of the garment to the cutting member, means connecting the drum to the support for rotation as a unit therewith about a common axis, an operating motor for said cutting member, and means for transmitting rotation from one of the motor driven parts to said drum and garment supporting form.

10. In a garment trimming machine, a rotatably mounted vertical spindle, a rotatable cutting member, a drum fixed to the spindle for directing the lower edge portion of a garment to said cutting member, a garment support above the drum axially movable relative to the spindle, means connecting said support with the drum for unitary rotation with the latter about the spindle axis, and means for vertically adjusting the garment support relative to the spindle and said drum.

11. In a garment trimming machine, a rotatably mounted garment support, a rotatable cutting member, an operating motor and driving connections between said motor and the cutting member, and means for feeding the garment material to said cutting member including a drum connected to rotate as a unit with the garment support, means for rotatively driving the drum and support, means movable relative to the drum and coacting therewith to feed the garment material to the cutting member, and means operatively connecting said two last named means with one of the motor driven parts.

12. In a garment trimming machine, a rotatably mounted garment support, a rotatable cutting member, an operating motor and driving connections between said motor and the cutting member, means for feeding the garment material to said cutting member including a drum connected to rotate as a unit with the garment support, vertically spaced rotatable members coacting with the drum wall to rotate said drum and garment supporting form, a pair of vertically spaced apart endless belts coacting with said drum wall to feed the garment material to the cutting member, and means operatively connecting said drum rotating members and the feed belts with one of the motor driven parts.

13. In a garment trimming machine, a rotatable cutting member, a garment supporting form and a drum mounted for unitary rotation, said drum directing the garment material to the cutting member, and an endless flexible feed belt in tangential relation to the drum wall and coacting therewith to feed the dress material to said cutting member.

14. In a garment trimming machine, a rotatable cutting member, a garment supporting form and a drum mounted for unitary rotation and vertically spaced apart relative to each other, said drum directing the garment material to the cutting member, an endless flexible feed belt in tangential relation to the drum wall and coacting therewith to feed the dress material to said cutting member, and means for vertically adjusting the garment support relative to said drum.

15. In a garment trimming machine, a rotatable cutting member, a garment supporting form and a drum mounted for unitary rotation, said drum directing the garment material to the cutting member, an endless flexible feed belt in tangential relation to the drum wall and coacting

therewith to feed the dress material to said cutting member, and means for operating the rotatable drum and support and the cutting member and feed belt from a common source of power.

16. In a garment trimming machine, a rotatable cutting member, a garment supporting form and a drum mounted for unitary rotation, said drum directing the garment material to the cutting member, and a pair of vertically spaced apart endless flexible feed belts coacting with the drum wall to feed the garment material to said cutting member.

17. In a garment trimming machine, a rotatable cutting member, a garment supporting form and a drum mounted for unitary rotation, said drum directing the garment material to the cutting member, a pair of vertically spaced apart endless flexible feed belts coacting with the drum wall to feed the dress material to said cutting member, and a single operating motor and means operated thereby for rotating the garment support and drum and for operating said feed belts and cutting member.

18. In a garment trimming machine, a garment support and feed drum mounted and arranged for unitary rotation about a common axis, a rotatable cutting member, an endless flexible feed belt coacting with the wall of said drum to feed the garment material to said cutting member, operating means for said feed belt, and means for mounting said belt and its operating means for bodily movement relative to the drum to dispose said feed belt in operative or inoperative relation to the drum wall.

19. In a garment trimming machine, a garment support and feed drum mounted and arranged for unitary rotation about a common axis, a rotatable cutting member, an endless flexible feed belt coacting with the wall of said drum to feed the garment material to said cutting member, operating means for said feed belt, and means for mounting said belt and its operating means for bodily movement about an axis parallel to the drum axis to dispose said feed belt in operative or inoperative relation to the drum wall.

20. In a garment trimming machine, a garment support and feed drum mounted and arranged for unitary rotation about a common axis, a rotatable cutting member, an endless flexible feed belt coacting with the wall of said drum to feed the garment material to said cutting member, a single operating motor for the garment support and drum, the cutting member, and the feed belt, and means for mounting the motor, cutting member and feed belt for unitary bodily movement about an axis parallel to the drum axis to dispose said cutting member and feed belt in operative or inoperative relation to the drum wall.

21. In a garment trimming machine of the character described, in combination means to support a garment, means to hold said garment supporting means, said garment supporting means being removable without manipulation of any parts thereof from the means for holding said supporting means, means to revolve said

holding means, and cooperating means on said garment supporting means and said holding means to cause said garment supporting means to revolve with said holding means.

5 22. In a garment trimming machine of the character described, in combination means to support a garment, a circular member disposed below said garment supporting means, said circular member being of an outer diameter at least 10 substantially equal to the largest lower dimension of said garment supporting means, means to revolve said garment supporting means and said member, a cutting station disposed in substantially fixed relationship to the axis of revolution of said garment supporting means, and means 15 cooperating with said circular member to feed portions of the garment to be trimmed to and past said cutting station at an angular speed substantially equal to the angular speed of said garment supporting means.

20 23. In a garment trimming machine of the character described, in combination means to support a garment, a circular member disposed below said garment supporting means, said circular member being of a diameter at least substantially 25 equal to the largest lower dimension of said garment supporting means, means to revolve said garment supporting means and said member, a cutting station disposed in substantially fixed relationship to the axis of revolution of said garment supporting means, means cooperating with said circular member to feed portions of the garment to be trimmed to and past said cutting station at an angular speed substantially equal to the angular speed of said garment supporting means, said means comprising a belt contacting said circular member through portions of the garment being trimmed, and means to move said belt at a linear speed substantially equal to the 30 linear speed of movement of the periphery of said circular member.

35 24. In a garment trimming machine, a garment support, a drum below said support, a trimming unit comprising a cutter mounted to rotate 40 in a horizontal plane adjacent the lower edge of the drum and relatively movable feeding means coacting with the outer surface of the drum to feed the garment material to the cutter, said unit further including drive means for said feeding 45 means having a part frictionally coacting with the drum above the plane of said rotary cutter, and power operated means connected to effect relative rotation between said trimming unit, the feed means and the drum about the axis of the 50 garment support.

55 25. The garment trimming machine as defined in claim 24, together with means for independently supporting and detachably mounting the trimming unit and power operated means in operative position relative to the garment support and the drum.

VICTOR J. SIGODA,
JERRY SIGODA,
JOSEPH COSENTINO.
